(57) **CLAIM**

The ornamental design for an identification card display, as shown and described.

DESCRIPTION

FIG. 1 is a perspective view of an identification card display showing our new design.

FIG. 2 is a front view for the identification card display shown in FIG. 1.

FIG. 3 is a rear view for the identification card display shown in FIG. 1.

FIG. 4 is a left side view for the identification card display shown in FIG. 1.

FIG. 5 is a right side view for the identification card display shown in FIG. 1.

FIG. 6 is a top view for the identification card display shown in FIG. 1;

FIG. 7 is a bottom view for the identification card display shown in FIG. 1;

FIG. 8 is an enlarged view of portion of the identification card display shown within the area labeled as **8** in FIG. 5; FIG. 9 is an enlarged view of portion of the identification card display shown within the area labeled as **9** in FIG. 5; and,

FIG. 10 is an enlarged view of portion of the identification card display shown within the area labeled as **10** in FIG. 6. The broken lines in the figures show portions of the display device that form no part of the claimed design.

1 Claim, 10 Drawing Sheets
